HENRY C. MILLER, OF MILWAUKEE, WISCONSIN.

LOCKING DEVICE FOR LOOSE-LEAF BINDERS.

1,119,523.

Specification of Letters Patent.

Patented Dec. 1, 1914.

Application filed May 12, 1913. Serial No. 766,999.

To all whom it may concern:

Be it known that I, HENRY C. MILLER, of Milwaukee, Wisconsin, have invented a Locking Device for Loose-Leaf Binders, of 5 which the following is a specification.

This invention relates to loose-leaf books of variable thickness, more particularly those having a back-cover to which a pair of upright standards are fixed and a front-10 cover provided with a locking-device adapted to clip said standards at any point of their length.

The object of my invention is to provide an improved type of locking-device and 15 more particularly one which cannot become opened accidentally as by shaking or dropping on the floor.

Heretofore locking-devices for this type 20 of binders have been customary in which a bolt or bar is moved endwise to grip or release the standards or posts; but said device held its place by friction merely.

A primary feature of my present invention 25 consists in providing a spring-lock which, when the locking-bar is in gripping position, positively holds it there, but which is released automatically by the same manipulation that slides the locking-bar back and therefore gives no additional trouble in 30 operating it.

Another feature of my invention consists 35 in novel means which I provide for causing the release of the gripping-devices and thereby releasing the standards.

The nature of my invention may best be 40 understood from a consideration of various concrete embodiments thereof, two of which are shown in the accompanying drawings, wherein—

Figure 1 is a perspective view of one 45 form of a complete loose-leaf book according to my invention; Fig. 2 is an elevation from the back of the binder of the cover-section and parts of the standards or posts, the locking-mechanism being shown in gripping position; Fig. 3 is a plan-view of the 50 left-hand end, as shown in Fig. 2, of the locking-mechanism, a part of the sheet-metal casing being cut away and the post or stand- ard shown in section; Fig. 4 is a longitudinal 55 central section through the locking-mechanism of the right-hand end thereof

as seen in Fig. 2, said mechanism being shown in the releasing position; Fig. 5 is an elevation from the back of a part of a 55 front-cover of a binder provided with another form of locking-mechanism and parts of the standards or posts, said mechanism being shown in the gripping position; Fig. 6 is an end-view thereof from the right-hand 60 end of Fig. 5; Fig. 7 is a longitudinal central section through the locking-mechanism shown in Fig. 5, of the right-hand end thereof as seen in said figure, the mechanism being here shown in releasing position; Fig. 8 is a plan-view of the same with 65 the top of the sheet-metal casing removed; and Fig. 9 is a plan of the gripping element of this form of the device as seen in Fig. 5.

The reference letters refer each to the 70 same part in each figure of the drawing.

The general parts illustrated in Fig. 1 comprise the back-cover *a*, the front-cover *b*, the leaves *c* and the standards or posts *d*, which latter are permanently fixed to the 75 back-cover *a*; and said posts may be of variable length, or in sections if desired, but as this idea is not relevant to the invention, it is not here shown.

The invention consists entirely in the spe- 80 cial form of locking-mechanism, designated as a whole *E*, which is contained in a sheet-metal box or housing *e'* mounted on the back-bar *b'* of the front-cover *b*. Said cover is here shown as being secured to the back-bar *b'* by means of a couple of prongs *e*² on its ends and a couple of rivets *e*³, which pass through the back-bar and are clenched or upset on the opposite side thereof. The interior of the housing *e'* is separated from 85 the back-bar *b'* (which is customarily cov- 90 ered with leather, canvas, etc., not here shown) by a flat plate *F*, which has holes through which said prongs *e*² and rivets *e*³ pass. Both the box *e'*, plate *F* and back-bar *b'* are provided with notches *e*⁴ which 95 extend from the back to the center of the housing for the purpose of enabling the cover to slip sidewise upon the posts as well as endwise; but this feature is not a necessary element of the invention.

The gripping-devices consist of a pair of spring-tempered plates *f'*, which are riveted to the plate *F* by rivets *f*², and whose free

ends are adapted when not otherwise restrained to press downward obliquely upon the sides of the posts d . The effect of this is that when the cover is in place on the posts, it will slide freely downward against the leaves c , but cannot be moved upwardly because the edges of the plates f' bind upon the posts. Thus the normal position of the gripping-devices is the gripping position. 10 For releasing the gripping means, I provide the locking-bar G , which is arranged to slide longitudinally within the casing e' and is of the same width as the latter interiorly. It has on its ends two depressed portions g' , 15 which are of such depth that they slide freely upon the plate F when the flat-portion of the bar G rests on the top of the box e' . An aperture or slot g^2 is formed in the bar G on the left-hand side of each depressed portion through which the spring-plates f' respectively extend. On the right-hand side of each depressed portion, the bar G is also slotted as shown at g^3 , the slot g^3 being of the same width as the diameter of the posts d , and narrower than 20 the slot g^2 , whereby the metal on each side of the slot is adapted to come against the under side of the spring-plate f' and lift it away from the post d when the bar G is shifted to the left, as shown in Fig. 4. It 25 will be understood, of course, that the slot g^3 is necessarily an open-ended slot whenever the side-slot e^4 is provided in the housing e' , to enable the cover to be removed sidewise as aforesaid; and in this case, the 30 prong g^4 on one side of the slot g^3 prevents the lateral withdrawal of the cover from the post in the locking-position.

Now, in order to prevent the accidental shifting of the bar G from the locking to the releasing-position, and at the same time provide means for shifting the locking-bar manually, I provide a spring-plate g^5 , secured to said bar by a rivet g^6 and carrying 40 a locking-pin g^7 and a manipulating-button g^8 , these passing through corresponding apertures g^9 and g^{10} in the bar G , and the shank of the button g^8 passing through a slot e^5 in the top of the casing e' . Said slot 45 is of such length that when the locking-bar is shifted to the locking-position of Figs. 1 and 2, the pin g^7 registers with the end of the slot e^5 , and the spring-plate g^5 raises it thereinto, so that the bar cannot now be shifted to releasing-position without manually depressing said pin g^7 , and this is effected by depressing the button g^8 , which 50 takes place by the same movement as that with which it is shifted endwise.

60 In the second form of my invention, Figs. 5 to 9 inclusive, the box or housing E' is substantially the same as in the first form, the slot e^5 , however, being omitted, and in place thereof is formed in one end of said

box a slot e^6 . The gripping-devices in this 65 case, consist of tilting spring-tempered plates F' , one of which is shown separately in Fig. 9; each of said spring-plates having pivot-ears f^3 formed on its ends which work in slots e^8 in the sides of the box E' . The 70 place of the locking-bar G is taken by a bar G' , which slides in like manner in the top of the box and has two downwardly curved tongues g^{11} , which both support the bar in 75 position and also serve to depress one end or other of the gripping-plates F' as the bar is shifted from one side to the other. These tongues g^{11} are formed by slitting the metal longitudinally along two parallel lines which lie on opposite sides of the post d 80 and bending the metal tongue so formed, thus giving a second tongue g^{12} , which in the locking-position extends across the open slot e^4 and prevents lateral withdrawal of the 85 cover from the posts.

The bar G' has a manipulating-tab g^{13} on its end, and said tab extends through the aperture e^6 and is turned up to give a convenient hold to the finger. Now, in order to lock the bar against accidental shifting, 90 the metal of the housing E' is formed with a downwardly depending tongue e^7 on the upper edge of the slot e^6 , and the tab g^{13} has a hole g^{14} formed therein which registers with said tongue e^7 when the bar is pushed in, as 95 clearly shown in Fig. 6. The resilient quality of the metal-bar G' causes the tab g^{13} to spring up and holds the hole g^{14} in engagement with the tongue e^7 , but it will be seen that the engagement is broken by the natural 100 effort of the finger in shifting the locking-bar to releasing position. In this case the action of the gripping-device F is regulated by the bar G' in a somewhat different manner from the first form of the invention. 105 When the bar is in locking-position, Fig. 5, the tongues g^{11} press upon the plates F' on the left of their pivots, and thus press the engaging ends f^4 thereof against the posts d ; but when the bar G' is shifted to the right, 110 the pressure of the tongues g^{11} is shifted to the right of the pivots f^3 and then the action is to raise the engaging ends f^4 away from the posts.

Various changes and modifications in the 115 constructions as herein shown may be made without departing from the spirit of my invention, and I wish it understood therefore, that the latter is not otherwise limited than by the proper scope of my claims.

Having thus described my invention, what I claim as new and desire to secure by Letters Patent is:

1. In a loose-leaf binder, the combination 125 with a post, a cover, and a locking-means on said cover having a shifting locking-bar; there being a pair of elements respectively on said locking-bar and a stationary part

adapted to positively engage one another in the locking-position and said elements being adapted to be resiliently disengaged.

2. In a loose-leaf binder, the combination 5 with a post, a cover, and a locking-means on said cover having a shifting locking-bar; there being a pair of elements respectively on said locking-bar and a stationary part adapted to positively engage one another in 10 the locking-position, and said elements being adapted to be resiliently disengaged by the same and manipulating-movement as that employed to shift said locking-bar.

3. In a loose-leaf binder, the combination 15 with the back-cover having an upright post and the front-cover adapted to slide on said post of a locking-mechanism on said front-cover adapted to engage said post; said locking-mechanism having a stationary and 20 a longitudinally shifting-member and said shifting-member having a locking and a releasing-position; the respective members having elements adapted to positively engage each other in the locking-position and 25 pressed into engagement by a spring; and a device adapted to simultaneously release said spring and shift said shifting-member.

4. In a loose-leaf binder, the combination with the back-cover having an upright post 30 and the front-cover adapted to slide on said post of a locking-mechanism on said front-cover adapted to engage said post; said locking-mechanism having a stationary and a longitudinally shifting-member and 35 said shifting-member having a locking- and a releasing-position; one of said members having a projecting element and the other a recess in which said projecting element is adapted to engage in the locking-position, 40 and a spring-device on said shifting-member adapted to hold said projecting element in engagement with said recess.

5. In a loose-leaf binder, the combination with the back-cover having an upright post 45 and the front-cover adapted to slide on said post of a locking-mechanism on said front-cover adapted to engage said post; said locking-mechanism having a stationary and a longitudinally shifting member and said 50 shifting-member having a locking- and a releasing position; one of said members having a projecting element and the other a recess in which said projecting element is adapted to engage in the locking-position, 55 a spring-device on said shifting-member adapted to hold said projecting element in engagement with said recess, and a manipulating element carried by said spring and adapted to be used simultaneously to release 60 said engagement and shift said shifting-member.

6. In a loose-leaf binder, the combination of the back-cover carrying one or more upright posts, a front-cover adapted to

slide thereon, and a locking-mechanism 65 mounted on said front cover, said locking-mechanism comprising one or more spring-plates, one for each post, mounted laterally on one side of the post and pressing downwardly against the same with its free end 70 whereby to permit downward but not upward movement of the cover on the post; and a longitudinally shifting-bar having one or more depressed portions, one for each post, each depressed portion provided on 75 one side with a slot through which passes the free end of the corresponding spring-plate and on the other side comprising one or more fingers adapted when shifted toward said spring-plate to raise the free end 80 of said spring-plate from said post.

7. In a loose-leaf binder, the combination of the back-cover carrying one or more upright posts, a front-cover adapted to slide thereon, and a locking-mechanism mounted 85 on said front-cover; said locking-mechanism comprising one or more spring-plates, one for each post, mounted laterally on one side of the post and pressing downwardly against the same with its free end whereby 90 to permit downward but not upward movement of the cover on the posts; and a longitudinally shifting bar having one or more depressed portions, one for each post, each depressed portion provided on one side with 95 a slot through which passes the free end of the corresponding spring-plate and on the other side comprising two fingers adapted, when shifted toward said spring-plate, to raise the free end of said spring-plate from 100 said post, and said locking-mechanism having one or more lateral notches, one for each post, through which the post is adapted to be inserted and one of the fingers of each depressed portion forming a prong which 105 is adapted in the releasing-position of said shifting-member to clear said notch and in the locking-position thereof to extend across the open side of said notch.

8. In a loose-leaf binder, the combination 110 of the back-cover carrying upright posts, a front-cover adapted to slide thereon, and a locking-mechanism mounted on said front-cover; said locking-mechanism comprising a closed box or housing, spring-plates, one for 115 each post, mounted laterally within said housing on one side of the post and pressing downwardly against the same with its free end whereby to permit downward but not upward movement of the cover on the posts; and a longitudinally shifting-bar within 120 said housing and sliding at the top thereof having one or more depressed portions one for each post, each depressed portion provided on one side with a slot through which 125 passes the free end of the corresponding spring-plate and on the other side comprising one or more fingers adapted when shift-

ed toward said spring-plate to raise the free end of said spring-plate from said post, said housing having a longitudinal slot therein, a spring-plate mounted at one of its ends on said longitudinally shifting-member, a manipulating-button mounted on said spring-plate and extending into said slot in the housing, and a projecting element mounted on said spring-plate and adapted

when said shifting-member is in the locking-position to register with said slot and abut against one end thereof.

In witness whereof I have hereunto set my hand in the presence of two witnesses.

HENRY C. MILLER.
